JOHN RALPH HOGE, OF TOLEDO, OHIO, ASSIGNOR TO OWENS-ILLINOIS GLASS COMPANY,
OF TOLEDO, OHIO, A CORPORATION OF OHIO

GLASSWARE ANNEALING LEER

Application filed May 25, 1928. Serial No. 280,431.

The present invention relates to improvements in glassware annealing leers and more particularly to that type of leer including an elongated tunnel or annealing chamber thru which ware is carried for tempering.

In glassware annealing leers of ordinary construction, the annealing chambers are provided with stationary roofs which are spaced above the leer conveyor a sufficient distance to permit annealing of a wide range of ware. Since the roofs are stationary, the dimensions of the zones thru which the ware passes remain unchanged regardless of whether large or small ware is being annealed. Obviously, when small ware is being annealed, it is desirable and, in fact, essential to good annealing to hold the hottest or most effective portions of the annealing gases in the lower areas of the chamber for direct contact with the ware. This condition is not readily obtainable in the average leer because of the presence of relatively large open spaces above the ware. Thus when small ware is being annealed the hotter portions of the annealing gases quickly pass over the ware and rise into the spaces above the latter so that the period of actual contact of the heated medium with the ware is quite short. Accordingly, the consumption of a great volume of fuel has been necessary in order to maintain a uniform high temperature in the heating zone. Overcoming the stated objections by increasing the volume of fuel consumed quite obviously involves a considerable increase in the cost of annealing and in addition does not always obtain the desired standard of annealing.

An object of the present invention is to provide novel means applicable to present-day leers to confine, to a considerable degree, the hottest portions of the annealing medium to areas actually occupied by the ware, irrespective of the size or type of ware being annealed.

Another object is to provide in a glassware annealing leer a series of adjustable baffle plates which operate to hold the most effective portions of an annealing medium in those areas thru which the ware to be annealed actually moves. Thus, the necessity for bringing the temperature of the upper areas

of the leer tunnel to the same degree as the areas thru which the ware passes, in order that the ware may be properly heated, is avoided. Accordingly, the volume of fuel consumed may be materially decreased. Also, substantially all of the heating medium introduced into the leer tunnel is applied to the ware and retained in contact therewith during a major portion of its period of effectiveness. This is in direct contrast to ordinary operating conditions in which there is a great loss in efficiency because the annealing medium passes rapidly over the ware and immediately moves into the upper areas of the leer wherein it performs no useful function.

Another object is to provide means whereby the baffle plates may be angularly adjusted independently of each other to thereby to a greater or less degree predetermine the temperature gradient thru given areas of the leer tunnel. Accordingly, the annealing medium may be confined at the forward end of the leer, almost entirely to the lower areas thru which the ware actually moves, and then allowed to move upwardly above the plane of the upper ends of the ware in a progressive fashion toward the delivery end of the leer as the medium moves rearwardly thru the leer tunnel. Thus, the effectiveness of the heat applied to the ware is gradually diminished in a manner to cool the ware without producing strains or stresses therein.

Other objects will be apparent hereinafter.

In the accompanying drawings:

Fig. 1 is a side elevation with parts in section, of a portion of a leer embodying the present invention.

Fig. 2 is a fragmentary elevation in detail illustrating the means for adjusting the baffle plates.

Fig. 3 is a fragmentary transverse sectional view illustrating the manner in which the baffle plates are supported in the leer tunnel.

Fig. 4 is a detail sectional elevation of the means for changing the angular relation between the baffle plates.

Fig. 5 is a sectional view of the parts shown in Fig. 4.

Fig. 6 is a fragmentary sectional view of another form of the invention in which the

baffle plates are suspended from supports arranged adjacent the roof of the leer.

In the drawings, the leer is illustrated as comprising an elongated tunnel or annealing chamber 10 having vertical side walls 11 connected together at their upper ends by a stationary horizontal roof 12. An endless ware conveyor 13 extends thru the leer tunnel, running over vertically spaced conveyor 10 rolls 14 at the forward end of the leer, said conveyor being suitably supported on a horizontal support 15. Means to supply an annealing medium to the annealing chamber 10 comprises, according to the present disclosure, a recuperator and heating unit 16 arranged between the horizontal reaches of the conveyor at the front end of the leer and return pipes or conduits 17 extending lengthwise of the leer and communicating with the annealing chamber by way of suction boxes 18. A suction fan 19 is interposed between the suction boxes and heating unit to force circulation of the annealing medium thru the annealing chamber and return pipes. The suction boxes 18 preferably include face plates 18^a, forming portions of the lining for the side walls of the annealing chamber 10 and provided with a series of perforations or exhaust openings 20 thru which the spent annealing medium is exhausted to the return pipes 17. A slide valve 21 (Figure 1) is arranged for vertical movement over one surface of the facing plate 18^a to predetermine the highest elevation at which the annealing medium is to be exhausted from the annealing chamber. The advantage of this feature and its effect upon operation of the leer will be apparent hereinafter.

A series of baffle plates 25 is arranged in the annealing chamber 10, said plates being spaced apart in the direction of the length of the leer conveyor 13. Each baffle plate is secured intermediate its upper and lower ends to a transverse rock shaft 26 (Figures 1 and 3), said shaft having its ends projected thru the side walls 11 of the leer and journaled in bearings 27 in said walls. Preferably sealing strips 28 of asbestos or like material are fixed to the side edges of the baffle plates 25 for a purpose hereinafter pointed out.

One end of the rock shaft 26 extends a considerable distance beyond the side wall 11 and is formed with an angular end portion 28 adapted for engagement with a tool by which said shaft may be given a rotary movement to change the angular position of the baffle plate. A gear or pinion 29 is loosely mounted on the rock shaft 26 and runs in mesh with the teeth of a rack bar 30 which may be reciprocated to angularly adjust a group of baffle plates. A pointer 31 (Figures 2, 4 and 5) is non-rotatively secured to the rock shaft 26 and is aligned with the corresponding baffle plate and co-operates with

graduations 32 arranged adjacent said pointer. Thus, the pointer 31 accurately indicates the angular position of the corresponding baffle plate, thereby facilitating adjustment of said plates.

A bearing plate or disk 33 is non-rotatively fixed to the shaft 26 inwardly from the pointer 31 and preferably in contact with the inner face of the latter. This disk also bears against the outer end of the adjacent bearing 27 for the rock shaft 26. A retaining nut 34 (Figures 4 and 5) is threaded on the rock shaft 26 outwardly from the opening 29 and is provided with teeth 35 on its inner face to engage the adjacent face of the hub 36 of said pinion. A lock nut 37 insures retention of the nut 34 in engagement with the pinion 29 so that driving connection between the pinion 29 and shaft 26 is obtained.

Mechanism to simultaneously change the angular position of the entire group of baffle plates includes a control rod 40 which connects the rack bars 30 to each other. Suitable supporting brackets 41 (Figures 2 and 4) are secured to one side wall of the leer, said brackets each comprising a substantially U-shaped portion providing a slideway 42 in which the control rod is slidingly arranged. Preferably, these brackets 41 are positioned immediately below the gears or pinions 29 in which position they insure meshing of the teeth of the rack bars and associated pinions. Reciprocation of the control rod 40 imparts a rocking movement to each transverse shaft 26 so that the baffle plates supported on said shafts are adjusted to change the degree of clearance between leer conveyor 13 and the lower ends of said plates and thereby vary the cross sectional area of the zone thru which the ware passes.

Mechanism to actuate the control rod 40 (Figure 2) may comprise a housing 43 mounted on one side wall of the leer and enclosing a worm gear 44 threaded on an extension 45 of the push rod 40, said worm gear running in mesh with a worm 46 to which rotary movement is imparted by manual rotation of a hand wheel 47, the latter being mounted on a shaft 48 which carries said worm 46.

A sectional partition 49 extending transversely of the annealing chamber is arranged at the inner end of the series of baffle plates to prevent or at least minimize the rearward movement of the annealing medium thru areas above the baffle plates. Movement of the annealing medium in these areas quite obviously would tend to reduce the effectiveness of the baffle plates in their functioning as a means for retaining the most effective portions of the annealing medium in proximity to the leer conveyor 13. This sectional partition preferably comprises a pair of plates 50 having their meeting marginal portions overlapping and slidingly contacting

with each other and suitably connected together to permit relative sliding. The lower plate is hinged to the lower edge of the innermost baffle plate 25 (Figure 1), while the upper plate 50 is hinged to a rod 51 in proximity to the roof of the annealing chamber.

In operating a leer of the type shown and including the features above set forth, the annealing medium is forced to circulate thru the recuperator and heating unit 16 and to move at variable rates of speed rearwardly thru the annealing chamber from which the medium is exhausted thru suction boxes 18. From the suction boxes, the annealing medium passes thru the return pipes 17 and suction fan 19 to the recuperator and heating unit. By arranging a series of baffle plates 25 in the annealing chamber and giving them an inclinaiton in the direction shown in Figure 1, the rearwardly moving annealing medium is, at least for the greater part, directed along a substantially horizontal path in the lower areas of the annealing chamber in direct contact with the ware passing thru these areas. The forced rearward movement of the annealing medium, together with the inclination of the baffle plates, practically insures retention of the most effective portions of the annealing medium in contact with

The length of the soaking period or heating zone may be predetermined by varying the relative angular positions of the baffle plates and by utilizing selected suction boxes along the annealing chamber. In this connection, it is evident that the first suction box, that is the one nearest the ware receiving end of the leer, may be opened so that the annealing medium is exhausted from the annealing chamber at this point. Thus, the heating zone is shortened the greatest possible extent and the temperature of the ware begins to decrease as it moves rearwardly beyond this suction box. To further assist in controlling the effectiveness and length of the heating zone and provide for gradual cooling of the ware beyond a predetermined point, the baffle plates from a point rearwardly may have their angles of inclination decreased to thereby progressively increase the height of the zone thru which the ware passes. Thus, the annealing medium is permitted to rise different distances above the ware as the latter moves thru the annealing chamber, with the result that the ware is gradually brought to atmospheric temperature.

By vertically adjusting the slide valves 21 of the suction boxes 18 to close all outlet openings above the lower edges of the baffle plates 25, the suction boxes materially assist said baffle plates in holding the annealing medium in the lower areas of the annealing chamber. It is evident that the suction applied to these boxes and the area thru which the ware passes, tends to move the annealing

medium thru the shortest path from the recuperator and heating unit 16 to the active exhaust openings 20 in the suction boxes and consequently very little of the annealing medium rises into the upper areas.

In another form of the invention (Figure 6), the baffle plates 25 are fixed at their upper ends to transverse rock shafts 26 arranged in proximity to the roof 12 of the annealing chamber. A connector rod 60 is connected at uniformly spaced points by pins 61 or the like to the lower portions of baffle plates 25 to insure retention of the plates in proper angular relation to each other. In this form, the mounting of the plates precludes the necessity for using the partition 49 (Figure 1), in that the probability of the annealing medium moving rearwardly above the baffle plates is practically eliminated. Means to adjust these baffle plates may comprise mechanism such as shown in Figure 2.

Modifications may be resorted to within the spirit and scope of the appended claims.

What I claim is:

1. In a glassware annealing leer, the combination of an annealing chamber, means to carry ware thru said chamber, a series of parallel shafts extending transversely of the direction of travel of the ware thru the chamber above the ware carrying means, baffle plates carried by said shafts, rack and pinion mechanism operable to simultaneously and uniformly vary the angular relation between the plates and conveyor, and means whereby each shaft may be rocked independently of the rack and pinion mechanism to change its angular relation to the other baffle plates and leer conveyor.

2. In a glassware annealing leer, an annealing chamber including a fixed roof, a leer conveyor spaced below the roof, and a series of inclined baffle plates arranged between the roof and conveyor in overlapping relation to each other.

3. In a glassware annealing leer, an annealing chamber including a fixed roof, a leer conveyor spaced below the roof, a series of inclined baffle plates arranged between the roof and conveyor in overlapping relation to each other, and means to adjust said baffle plates to vary the spaced relation between the leer conveyor and the lower ends of the baffle plates.

4. In a glassware annealing leer, an annealing chamber including a fixed roof, a leer conveyor spaced below the roof, a series of inclined baffle plates arranged between the roof and conveyor in overlapping relation to each other, means to vary the angular relation between the baffle plates, and means whereby the entire series of plates may be angularly adjusted in unison to vary the spaced relation between the lower ends of the plates and the leer conveyor.

5. In a glassware annealing leer, an an-

nealing chamber having a stationary roof, a
ware conveyer spaced below the roof, a series
of pivoted baffle plates arranged between the
conveyer and roof and so relatively spaced
that they may be adjusted to provide a sub-
stantially horizontal partition, and means
for angularly adjusting the baffle plates.

Signed at Toledo, in the county of Lucas
and State of Ohio, this 23rd day of May,
1928.
